Primary Examiner — John Windmuller*Assistant Examiner* — Steven J Czyz(74) *Attorney, Agent, or Firm* — Honigman LLP(57) **CLAIM**

The ornamental design for a bio-clamp, as shown and described.

DESCRIPTION

FIG. 1 is a front left side perspective view of a bio-clamp showing our new design;

FIG. 2 is a left side view thereof;

FIG. 3 is a right side view thereof;

FIG. 4 is a top view thereof;

FIG. 5 is a bottom view thereof;

FIG. 6 is a front elevation view thereof; and,

FIG. 7 is a rear elevation view thereof.

1 Claim, 7 Drawing Sheets(56)
